INVENTOR:

William G. Collins,

BY Drake & C. ATTY'S.

UNITED STATES PATENT OFFICE.

WILLIAM GEORGE COLLINS, OF NEW YORK, N. Y.

DESIGN FOR A PATTERN FOR PLUSH OR PILE FABRICS.

SPECIFICATION forming part of Design No. 25,742, dated June 30, 1896.

Application filed April 25, 1896. Serial No. 589,126. Term of patent 14 years.

To all whom it may concern:

Be it known that I, WILLIAM GEORGE COLLINS, a citizen of the United States, residing at New York, in the county of New York and State of New York, have invented and produced a new and original Design for a Pattern for Plush or Pile Fabrics; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan representing a portion of my newly-designed plush or pile fabric, and Fig. 2 is an enlarged section taken at line *x*. Fig. 3 is a plan on the scale of Fig. 2.

The leading feature of my design consists in the pattern for plush or pile fabrics with narrow raised stripes which alternate with wide ones, the grooves showing transverse ribs or "terry" weave threads.

In the said drawings, *a a* indicate the narrow raised stripes, which are in groups of two or more, and *b b* are wide stripes alternating with the said groups, as shown. In the grooves, between the raised stripes of pile, the fabric presents ornamental loop-threads technically known as "terry" weave, which give a transversely-ribbed effect of ornamentation. Said stripes *a b* lie parallel with one another, and are not broken by cross-stripes or the like, but present smooth unbroken surfaces, as indicated in Fig. 2.

35

What I claim is—

The design for a pattern for plush or pile fabrics, substantially as set forth.

In testimony that I claim the foregoing I have hereunto set my hand this 27th day of March, 1896.

WILLIAM GEORGE COLLINS.
